UNITED STATES PATENT OFFICE.

MAYO S. PURPLE, OF EAST HAMPTON, CONNECTICUT.

DESIGN FOR A SIGNALING-HORN.

43,158.

Specification for Design.

Patented Oct. 15, 1912.

Application filed August 10, 1912. Serial No. 714,478. Term of patent 7 years.

To all whom it may concern:

Be it known that I, MAYO S. PURPLE, a citizen of the United States, residing at East Hampton, in the county of Middlesex and State of Connecticut, have invented a new, original, and ornamental Design for a Signaling-Horn, of which the following is a specification, reference being had to the accompanying drawing, forming a part thereof.

Figure 1 is a perspective view looking

from the front end of the device showing the new design. Fig. 2 is a view in side elevation of the device.

I claim:

The ornamental design for a signaling horn as shown.

MAYO S. PURPLE.
